UNITED STATES PATENT OFFICE.

NIELS C. Y. GUNDHOLM, OF BRADFORDVILLE, FLORIDA.

PLOW ATTACHMENT.

No. 918,445.

Specification of Letters Patent.

Patented April 13, 1909.

Application filed April 27, 1908. Serial No. 429,421.

To all whom it may concern:

Be it known that I, NIELS C. Y. GUNDHOLM, citizen of the United States, residing at Bradfordville, in the county of Leon and 5 State of Florida, have invented certain new and useful Improvements in Plow Attachments; and I do declare the following to be a full, clear, and exact description of the invention, such as will enable others skilled in 10 the art to which it appertains to make and use the same.

This invention relates to attachments for plows.

The object of the invention is to provide 15 an attachment of this character by means of which the soil turned over by the mold-board of the plow will be cultivated, harrowed and rolled in one operation.

A further object is to provide means 20 whereby the attachment may be readily applied to and removed from the plow.

With these and other objects in view, the 25 invention consists of certain novel features of construction, combination and arrangement of parts as will be described and particularly pointed out in the appended claim.

In the accompanying drawings, Figure 1 is a side view of the plow showing the application of the invention thereto; Fig. 2 is a 30 top plan view of the same; Fig. 3 is a vertical cross sectional view on the line 3—3 of Fig. 2; and Fig. 4 is a plan view of the shoe employed to facilitate the moving of the plow from place to place.

35 Referring more particularly to the drawings, 1 denotes the plow, which is here shown as a wooden beam plow, and to the beam immediately in front of the standard is secured a right-angular supporting bar, 2, said bar 40 being provided on its underside, adjacent to its inner end, with a right-angularly formed beam-engaging projection, 3, which is adapted to be engaged with one side and the bottom of the beam, while the inner end of the 45 bar, 2, engages the upper side thereof, thus embracing the beam on three sides. The ends of the projection, 3, and the bar, 2, extend beyond the opposite side of the beam, and on said ends is arranged a clamping 50 plate, 4, which is adapted to fit against the adjacent side of the beam. The ends of the projection, 3, and bar, 2, are threaded, and on said threaded ends is adapted to be 55 screwed clamping nuts, whereby the plate, 4, is tightly clamped against the beam, thereby rigidly securing the bar, 2, in place. The

bar, 2, is further held in position by means of set screws, 5, which are arranged therein as shown. The bar, 2, is further secured in position on the beam of the plow by means of 60 an obliquely disposed brace bar, 6, one end of which is bolted to the bar, 2, and the opposite end bolted to the plow beam.

On the underside of the bar, 2, adjacent to its outer end, is secured a series of tapered 65 spacing blocks, 7, between which are secured the tapered forward ends of a series of implements. The tapered ends of the implements are preferably secured between the spacing block 7 by means of a clamping bar, 8, arranged beneath the same and bolted to the bar at its opposite ends, and are further secured by means of bolts, 9, which are inserted in alined apertures in the bar, 2, the tapered ends of the implements and in the 70 clamping bar 8, thereby firmly securing the implements in position on the end of the bar.

The implements hereinbefore mentioned comprise a cutting blade, 10, which is formed on the end of a spring-arm, 12, the 75 forward end of which is tapered and secured between the spacing blocks on the lower side of the bar, 2. Another implement secured to the bar, 2, comprises a spring-arm, 13, having its outer end provided with a half-twist 80 or turn, and to said turned end is bolted or otherwise secured the harrow teeth, 14. Another implement carried by the bar consists of an arm, 15, the rear end of which is tapered and bent at right-angles to form a 85 covering or scraping blade, 16. Also secured to the bar, 2, is a pair of rearwardly 90 projecting spring arms, 17 and 18, the arm, 18, being secured to the outer end of the bar, 2, and is provided substantially midway between its ends with an offset portion, 19. Between the rear ends of the arms, 17 and 18, is revolubly mounted a roller, 20. On the arm, 17, is formed a loop, 21, with which is 95 adapted to be engaged the outer end of a 100 brace bolt, 22, the inner end of which is secured in a loop, 23, arranged on one of the plow handles.

In use, the cutting blade, 10, first engages the soil turned over by the mold-board of the 105 plow and cuts or splits the furrow, after which the soil is engaged by the scraping blade, 16, and is then engaged by the harrow teeth, 14, which harrow and cultivate the soil and break up the lumps, or clods, after 110 which the roller engages the soil and crushes or pulverizes the same, these operations all

taking place during the plowing of the ground, thus avoiding the necessity of going over the ground with separate harrowing and rolling machines.

5 Secured to the plow beam in front of the share, is a fender, 24, which preferably consists of a pair of downwardly-extending rearwardly-inclined arms, the upper ends of which are bolted to the opposite side of the beam, while their lower ends are spaced apart and secured together by a cross bar, 25. One of the arms of the fender, 24, is preferably offset so as to provide sufficient space between the arms to cause them to force or 10 turn down all weeds so that they may be covered by the turning of the soil. The fender is held in position by means of a coiled spring, 26, which is secured at its lower end to the cross bar, 25, and at its upper end to 15 the underside of the plow beam.

In order that the plow and its attachments may be readily moved from place to place, I provide a shoe, 27, which consists of a flat metal plate, one end of which is tapered to a 20 point and is provided with a cross strip, 28, adapted to receive the point of the plow share when the latter is applied to the shoe. On the upper side of the plate, 27, of the shoe, adjacent to one edge, are secured parallel 25 cleats 29, between which is formed a space to receive the lower edge of the landside of the plow share. By engaging the end or point of the plow share with the strip, 28, and the landside with the strip, 29, the plow may be 30 readily drawn from one field to another, thus obviating the necessity of carrying or dragging the plow to one side, and preventing the breaking of any of the implements carried by 35 the plow.

40 While the attachment is herein described and shown as applied to a wooden beam plow, it is obvious that the same may be se-

cured to iron beam plows in practically the same manner in which it is attached to the wooden beam.

45 From the foregoing description, taken in connection with the accompanying drawing, the construction and operation of the invention will be readily understood without requiring a more extended explanation.

50 Various changes in the form, proportion and the minor details of construction may be resorted to without departing from the principle or sacrificing any of the advantages of the invention as defined in the appended 55 claim.

Having thus described my invention, what I claim as new and desire to secure by Letters-Patent, is:

56 In an attachment for plows, a supporting bar adapted to be secured at one end to the beam of the plow, said bar having on its under side a series of tapered notches, spring supporting arms carrying cultivating implements, said arms having tapered ends to engage the tapered notches in said bar, a clamping plate on the under side of said bar and engaged with the ends of said spring arms, fastening bolts passed through said bar and plate and the tapered ends of said arms, a 60 brace bar connected at one end to said supporting bar and at its opposite ends to said plow beam, handles on the plow, and a brace bolt connected to one of the spring arms and to one of said handles whereby said arm is 65 held against lateral strain.

70 In testimony whereof I have hereunto set my hand in presence of two subscribing witnesses.

NIELS C. Y. GUNDHOLM.
